UNITED STATES PATENT OFFICE.

MILLER REESE HUTCHISON, OF SUMMIT, NEW JERSEY.

MECHANICALLY-ACTUATED ACOUSTIC DIAPHRAGM.

No. 888,643.

Specification of Letters Patent. Patented March 31, 1908.

Original application filed May 16, 1907, Serial No. 373,946. Divided and this application filed November 26, 1907. Serial No. 403,932.

To all whom it may concern:

Be it known that I, MILLER REESE HUTCHISON, a citizen of the United States, and a resident of Summit, in the county of Union 5 and State of New Jersey, have invented certain new and useful Improvements in Mechanically-Actuated Acoustic Diaphragms, of which the following is a specification.

This invention relates to signals or alarms, particularly such as are intended to perform functions similar to those of fog signals, boat whistles, automobile horns, etc.

It relates particularly to that class of such signals or alarms in which the sound wave is generated by a diaphragm adapted for forcible bodily displacement by mechanical means.

In one of my prior applications, Ser. No. 305,933, filed March 14, 1906, I have disclosed and have made broad claims to the 20 basic features of the mechanically displaced diaphragm alarm or signal, and also claims for the broad combinations in such devices of a cam as the actuating member for effecting the forcible bodily displacement of the diaphragm. In said prior applications, I have disclosed and claimed various forms of connection whereby relatively great power may be applied through the cam or other driving member to the diaphragm so as to produce a 25 signal of great volume without causing excessive wear and tear. Furthermore, in my more recent application, Serial No. 373,946, filed May 16th, 1907, I have shown and described the specific details of construction 30 herein shown, and it is to be understood that my present application is a division of said application Serial No. 373,946, and is intentionally limited to certain specific features. The various broad combinations and 35 the broad inventions are claimed in the several prior applications referred to.

In devices of the above type, it is desirable to mechanically apply the power in such manner as to insure high velocity and great 45 amplitude of bodily displacement in a direction perpendicular to the diaphragm and at the same time to minimize the production and destructive effects of vibratory stresses in other directions. When such devices are 50 made of ample proportions and capable of utilizing considerable amounts of power, as is necessary for the above described purposes the forcible bodily displacement of the diaphragm may be simply and economically effected by means of a driving member which

may or may not move in a direction exactly normal to the surface of the diaphragm. If the power of the driving member is applied to the diaphragm through the medium of a cam projection having a movement across 60 the face of the diaphragm at the point of contact therewith, as in the case of a rotary cam, the direct frictional wear and concussion of the cam may be resisted by forming or providing the diaphragm with a wear 65 piece which may be an anvil with a face of hardened steel. I have discovered, however, that there may be a further destructive effect of concussion or vibration as well as of localized bending due to the velocity and amplitude of the forcible bodily displacement, 70 by which effects the metal of the diaphragm may be quickly fatigued and ruptured. This seems to be due to the fact that notwithstanding all refinements of adaptation of 75 shape and construction of driving member to driven member, the high velocity of the movements and considerable amounts of power transmitted, give rise to various localized bending and vibratory stresses, some of 80 which are not developed at lower speeds, and which at the higher speeds may be of pronounced character and destructive effect.

I have discovered that disruptive wear and tear of the diaphragm from various causes, 85 including those above suggested, may be obviated by convexing or rounding off the anvil faces where they contact with the diaphragm so as to prevent fatigue and cutting action, which I have found results from violent localized bending and other effects of 90 the high velocity movement and vibrations of the parts where the contact faces are plane and their peripheral edges sharp. The rounding of the edges or convexing of the 95 surfaces of the contact of the anvil with the diaphragm, is especially important on the sides which lie in the direction of transverse movement of a driving member, and the convexing may be decreased or even omitted in 100 directions at right angles thereto; but it is usually preferable to extend the rounding or beveling more or less uniformly around a complete annulus extending a greater or less distance toward the center of each clamping 105 face.

A second feature of my invention consists in a special arrangement of a diaphragm formed with a tough grain or fibrous structure, the fibers being approximately parallel 110

with each other and with the surface of the diaphragm. A suitable material for such a diaphragm is steel of fine quality formed by the rolling process. Such material is very much tougher in any other direction than it is in a direction at right angles to the fiber, and one feature of my invention consists in so arranging matters as to make certain that where the direction of movement of the driving member has any lateral component not normal to the diaphragm, such component or components will take effect in the general direction of the fiber, rather than transversely thereto.

While I fully show, describe, and point out in the appended claims certain novel features of construction, arrangement, and operation which characterize my invention, it will be understood by those skilled in the art that various omissions, substitutions, and changes in the forms, proportions, sizes, and details of the device and of its operation, may be made without departing from the terms of my claims.

My invention will be more fully understood in connection with the accompanying drawings, in which

Figure 1 is a section taken on the line $x-x$, Fig. 2; Fig. 2 is a section on the line $y-y$, Fig. 1, and Fig. 3 is a face view of the diaphragm showing the anvil in plan.

The diaphragm 1 may be of any suitable material, but is preferably of tough metal, and if of corrodible material, may be formed or provided with a protective covering. The diaphragm need not be of pure iron, because it is not intended for purposes involving electric or magnetic action. I find that fine quality sheet steel is a good material. The rolling process gives a hard surface finish tending to resist corrosion. I have discovered that rolled steels having a fibrous structure such as vanadium, nickel, or nickel-chrome steel, particularly those varieties having great elasticity and freedom from crystallizing tendency are very satisfactory materials, when arranged and used in accordance with my invention.

Since the diaphragm is intended for high velocity operation giving rise to relatively great instantaneous stresses, it is preferably made of ample diameter and thickness. It is provided with special means for protecting it against damage by action of the driving member which applies the power thereto.

As shown in the drawing, the power is applied through contact with or impact upon a wear piece 2' of anvil 2. This is preferably a separate piece of self-hardening steel, suitably secured to the diaphragm and not integral therewith. One feature of my invention consists in special construction of means for attaching the anvil to its diaphragm. The connection consists of a projection or shank 3, extending through a perforation 4,

in the diaphragm, and secured on the back-side thereof and preferably by permanently upsetting or deforming one of the engaging members, as by riveting the material of the shank over a washer or nut 5 surrounding the shank. The shank serves to center the parts in operative relation to the diaphragm and functionally it constitutes a tension-member to withstand the lateral displacing effort of the cam or other striking member and of the inertial stresses which result from the vibration of the parts.

As shown in the drawing, the shank 3 is itself malleable and is riveted over the washer 5 so as to hold the

wear piece tightly clamped to the diaphragm.

Whatever may be the specific means em-

ployed for holding the wear piece or anvil secured to the diaphragm, it is extremely important that the edges of the faces of the two co-operating members adjacent the dia- 85 phragm, be rounded as at 6 and preferably convexed or beveled off, as at 6', in order to prevent the above described destructive action on the diaphragm, which would result from sharp edges and in less degree from plane faces.

By convexing or beveling the faces as well as rounding off the edges of the anvil securing members, the bending effects and vibratory stresses are less localized and are caused to take effect more gradually, being

spread out in such manner as to effectually cushion their violence and lessen their de- 95 structive effects without decreasing the amplitude or velocity of the bodily displacement of the diaphragm. This feature is of

great advantage even where the driving member delivers its power in a direction ex- 100 actly perpendicular to the diaphragm. The convexing or beveling off of the edges may

be varied both in degree and in its extent 105 about the periphery or toward the shank 3.

Preferably, however, the rounding or beveling is carried back on a straight or convex

bevel forming a flat truncated cone or seg- 110 ment of a sphere extending nearly or quite to the shank 3.

The form and extent of the variation from a true plane by convexing or

beveling will vary somewhat with the size, stiffness and amplitude of vibration of the

diaphragm; but one skilled in the art will un- 115 derstand that the space for play of the dia-

phragm at the free edges of the anvil securing

surfaces, will preferably be sufficient to

avoid too localized or abrupt bending of the

diaphragm, even when it is bent by the driv- 120 ing to the extreme limit for which it is de-

signed. In actual practice, the angle of the

beveling or curvature of the convexing is

usually less than that indicated in the draw- 125

ings.

A convenient form of anvil 2 consists of a

small cylinder 2' of self-hardening steel fitted

into a recess 7, and there secured in any de-

sired manner, as by upsetting or riveting

down the lips 8, 9, preferably so securely as

to prevent all possibility of rotary or of end-
wise movement of the cylinder. By making
these lips 8, 9 and the shank 3 of one integral
piece of malleable metal, many mechanical
5 difficulties and defects are avoided.

The above features of construction are of
great advantage in connection with any me-
chanically driven diaphragm, regardless of
whether the diaphragm is formed of a homo-
10 geneous structureless material, or one having
a distinct grain. Where the metal has a
grain, there is another feature of my inven-
tion which consists in a special directional
relation between the grain of the diaphragm
15 and the direction of presentation of the wear
piece to its driving member. Indeed, the di-
rection of the grain is equally important,
whether the wear piece or anvil is a separate
piece secured to the diaphragm or is formed
20 integrally with the diaphragm. I have dis-
covered that where the diaphragm is of
rolled steel or similar grained material and
the contact lines of the wear surface or anvil
are parallel with the grain or fiber of the steel,
25 the diaphragm is more likely to crack or wear
out, and one part of my invention consists in
so relating the anvil to the diaphragm that the
impact surface is presented to its driving
member in the general direction of the grain,
30 so that when the cam or other driving mem-
ber strikes the anvil, any vibratory stresses
in directions other than normal to the plane
of the diaphragm, may take effect in direc-
tions of greater, rather than less strength of
35 fiber. In Fig. 3 of the drawing, I have in-
dicated by parallel broken lines the general
direction of trend of the grain of the fiber of
the diaphragm. It will be noted that the
wear or anvil surfaces are presented for im-
40 pact in the direction of the grain of the metal,
the long straight-line elements of the wear
surfaces of the cylinder being directed trans-
versely of the fiber. If the wear surface is
integral with the diaphragm, the directional
45 relation of impact with respect to the grain
of the metal will be the same as above.

The surface of engagement between the
diaphragm and the anvil or its securing
means may be formed or arranged to tightly
50 clamp the diaphragm at the center and to
leave an annular space for play of the dia-
phragm engaging faces of the securing mem-
bers at the free edges thereof. I have found,
however, that securing members originally
55 formed so as to have a tight clamping engage-
ment at the center sometimes work loose, or
may intentionally be arranged loosely, if so
desired; but even in the latter case, if the
free edges are suitably rounded, or are of
60 sufficiently soft material so as not to have a
cutting action, the device will operate satis-
factorily, but the annular space for such play
of the diaphragm should be predetermined
by and made approximately proportional to

the maximum proposed amplitude of vibra- 65
tion of the diaphragm when in use.

I claim:

1. An acoustic diaphragm, consisting of a
sheet of rolled steel and an attached impact
or wear piece for receiving and transmitting 70
mechanically applied power to forcibly flex
the diaphragm, such wear piece comprising
clamping members on opposite sides of the
diaphragm, secured in position by a tension
member extending through a perforation in 75
the diaphragm, one or more surfaces of en-
gagement between the diaphragm and clamp-
ing members being relieved or cut away to-
ward the periphery so as to have a decreased
clamping engagement from the perforation 80
outwardly when the diaphragm is in normal
position, and to have an increased engage-
ment with the concave surface of said dia-
phragm as it is flexed by application of power
through said impact or wear piece, substan- 85
tially as and for the purpose described.

2. An acoustic diaphragm and an attached
impact or wear piece for receiving and trans-
mitting mechanically applied power to for-
cibly flex the diaphragm, such wear piece 90
comprising diaphragm engaging members on
opposite sides of the diaphragm, secured in
position by a tension member extending
through a perforation in the diaphragm, one
or more surfaces of engagement between the 95
diaphragm and the engaging members being
relieved or cut away toward the periphery so
as to have a decreased engagement near the
free edges when the diaphragm is in normal
position, and to have an increased engage- 100
ment with the concave surface of said dia-
phragm as it is flexed by application of power
through said impact or wear piece, substan-
tially as and for the purpose described.

3. An acoustic diaphragm and an attached 105
impact or wear piece for receiving and trans-
mitting mechanically applied power to for-
cibly flex the diaphragm, such wear piece
comprising diaphragm engaging members on
opposite sides of the diaphragm, secured in 110
position by a tension member extending
through a perforation in the diaphragm, the
diaphragm engaging the face of the impact or
wear piece being relieved or cut away toward
the free edges so as to have an increased en- 115
gagement with the concave surface of said dia-
phragm when it is flexed by application of
power through said impact or wear piece,
substantially as and for the purpose de-
scribed.

4. An acoustic diaphragm, consisting of a
sheet of rolled steel and an attached impact
or wear piece for securing and transmitting
mechanically applied power to forcibly flex
the diaphragm, such wear piece comprising 125
clamping members on opposite sides of the
diaphragm, secured in position by a tension
member extending through a perforation in

the diaphragm, the edges of the diaphragm engaging face being rounded so as to prevent abrupt flexing or cutting action when the diaphragm is flexed by application of power through said impact or wear piece, substantially as and for the purpose described.

5. An acoustic diaphragm and an attached impact or wear piece for receiving and transmitting mechanically applied power to forcibly flex the diaphragm, such wear piece comprising diaphragm engaging members on opposite sides of the diaphragm, secured in position by a tension member extending through a perforation in the diaphragm, the 10 edges of the diaphragm engaging face being rounded so as to prevent abrupt flexing or cutting action when the diaphragm is flexed by application of power through said impact or wear piece, substantially as and for the 15 purpose described.

6. An acoustic diaphragm and an attached impact or wear piece for receiving and transmitting mechanically applied power to forcibly flex the diaphragm, such wear piece comprising diaphragm engaging members on opposite sides of the diaphragm, secured in position by a tension member extending through a perforation in the diaphragm, the edges of the diaphragm engaging faces being 20 rounded so as to prevent abrupt flexing or cutting action when the diaphragm is flexed by application of power through said impact or wear piece, said diaphragm being formed of metal having a fibrous or grained structure 25 and said impact or wear piece having its impact or wear surface extending transversely of the general direction of trend of the fiber of the metal, so that said surface is presented for engagement or impact in a direction of 30 greater strength of the metal, substantially as and for the purpose described.

7. An acoustic diaphragm and an attached impact or wear piece for receiving and transmitting mechanically applied power to forcibly flex the diaphragm, such wear piece comprising diaphragm engaging members on opposite sides of the diaphragm and a tension member extending through a perforation in the diaphragm and upset or riveted 45 to hold said parts in position, the edges of the diaphragm engaging face being rounded so as to prevent abrupt flexing or cutting action when the diaphragm is flexed by application of power through said impact or wear piece, said diaphragm being formed of metal having a fibrous or grained structure and said impact or wear piece having its impact or wear surface extending transversely of the 50 general direction of trend of the fiber of the metal, so that said surface is presented for engagement or impact in a direction of greater strength of the metal, substantially as and for the purpose described.

8. An acoustic diaphragm, consisting of a

sheet of rolled steel and an attached impact 65 or wear piece for receiving and transmitting mechanically applied power to forcibly flex the diaphragm, such wear piece comprising clamping surfaces on opposite sides of the diaphragm, and a tension member extending 70 through a perforation in the diaphragm and upset or riveted to hold said parts in position, the edges of an element at the diaphragm engaging face being rounded so as to prevent abrupt flexing or cutting action 75 when the diaphragm is flexed by application of power through said impact or wear piece, substantially as and for the purpose described.

9. An acoustic diaphragm, consisting of a sheet of rolled steel and an attached impact 80 or wear piece for receiving and transmitting mechanically applied power to forcibly flex the diaphragm, such wear piece comprising clamping members on opposite sides of the diaphragm, secured in position by a tension 85 member riveted through a perforation in the diaphragm, one or more surfaces of engagement between the diaphragm and the clamping members being relieved or cut away toward the free edge of the clamp so as to have 90 a decreased clamping action toward the free edges when the diaphragm is in normal position, and to have an increased engagement with the concave surface of said diaphragm as it is flexed by application of power through 95 said impact or wear piece, substantially as and for the purpose described.

10. An acoustic diaphragm consisting of a sheet of elastic metal and an impact or wear piece fixed in position for receiving and transmitting mechanically applied power to forcibly flex said diaphragm, the diaphragm engaging surface of said impact or wear piece being slightly beveled or convexed away from the normal face of the diaphragm so as 100 to engage the diaphragm over a given area when in its normal position, and then over a larger area as it is concaved by forcible application of the power through said impact or wear piece, substantially as and for the 105 purpose described.

11. An acoustic diaphragm, consisting of a sheet of elastic metal and an attached impact or wear piece for receiving and transmitting mechanically applied power to forcibly flex 110 the diaphragm, such wear piece comprising clamping members on opposite sides of the diaphragm, secured in position by a tension member extending through a perforation in the diaphragm, the surfaces of engagement 115 of diaphragm and clamp being formed and arranged so as to clamp the diaphragm adjacent the perforation therethrough, and to present an outer annular space slightly convexed so that the surfaces of contact will 120 come into contact over a gradually increasing area and thereby produce a cushioning 125 effect when said diaphragm is forcibly flexed

by application of power through said impact or wear piece, substantially as and for the purpose described.

12. An acoustic diaphragm, consisting of a sheet of rolled steel, an impact or wear piece for securing and transmitting mechanically applied power to forcibly flex the diaphragm and means for securing the impact or wear piece in operative relation to the diaphragm, said impact or wear piece having a diaphragm engaging face normally in contact with the surface of the diaphragm adjacent the point of attachment, and having an annular outer portion radially convexed or beveled away from the surface of the diaphragm, substantially as and for the purpose described.

13. An acoustic diaphragm formed of metal having a fibrous or grained structure, and provided with a wear or impact element having a surface extending transversely of the general trend of the grain of the metal, substantially as and for the purpose described.

14. An acoustic diaphragm formed of rolled steel, and provided with a wear or impact element having a surface extending transversely of the general trend of the fiber of the steel, substantially as and for the purpose described.

15. An acoustic diaphragm formed of rolled steel, and provided with an anvil riveted thereto with its wear surface presented for engagement or impact in the direction of trend of the grain of the diaphragm, substantially as and for the purpose described.

16. An acoustic diaphragm, consisting of a sheet of elastic metal provided with an impact or wear piece for receiving and transmitting mechanically applied power to forcibly flex the diaphragm, said impact or wear piece being formed with hard surface for impact or wear, and a malleable metal surface engaging the diaphragm, the center of the diaphragm engaging face of said impact or wear piece being attached to said diaphragm and the free edges thereof being rounded so as to prevent abrupt flexing or cutting action when the diaphragm is flexed by application of power through said impact or wear piece, substantially as and for the purpose described.

17. An acoustic diaphragm, consisting of a sheet of rolled steel and an attached impact or wear piece for receiving and transmitting mechanically applied power to forcibly flex the diaphragm, such wear piece comprising malleable metal clamping surfaces on opposite sides of the diaphragm, and a tension member extending through a perforation in the diaphragm and upset or riveted to hold said parts in position, the edges of the diaphragm engaging face being rounded so as to prevent abrupt flexing or cutting action when the diaphragm is flexed by application

of power through said impact or wear piece, substantially as and for the purpose described.

18. An acoustic diaphragm consisting of a sheet of elastic metal and an impact or wear piece fixed in position for receiving and transmitting mechanically applied power to forcibly flex said diaphragm, the diaphragm engaging surface of said impact or wear piece being of malleable metal and slightly beveled or convexed away from the normal face of the diaphragm so as to engage the diaphragm over a given area when in its normal position, and then over a larger area as it is concaved by forcible application of the power through said impact or wear piece, substantially as and for the purpose described.

19. An acoustic diaphragm consisting of a sheet of hard elastic metal provided with an anvil of malleable metal and a hard metal element having a wear surface, said anvil being formed with a recess containing such hard metal element held therein by upsetting and having a shank riveted through a perforation in the diaphragm, substantially as and for the purpose described.

20. An acoustic diaphragm consisting of a sheet of hard elastic metal provided with an anvil of malleable metal and a hard metal element having a wear surface, said anvil being formed with a recess containing such hard metal element held therein by upsetting and having a shank riveted through a perforation in the diaphragm, the diaphragm engaging face or faces being tightly clamped to the diaphragm adjacent the perforation, but out of contact therewith at the free edges, substantially as and for the purpose described.

21. An acoustic diaphragm consisting of a sheet of hard elastic metal, provided with an anvil of malleable metal and a hard metal cylinder, said anvil being formed with a cylindrical recess containing such hard metal cylinder held therein by upsetting of the metal of said anvil one side of such cylinder being exposed, substantially as and for the purpose described.

22. An acoustic diaphragm consisting of a sheet of hard elastic metal, provided with an anvil of malleable metal and a hard metal cylinder, said anvil being formed with a cylindrical recess containing such hard metal cylinder held therein by upsetting of the metal of said anvil one side of such cylinder being exposed, an integral shank projecting from said anvil being riveted against a washer on the rear side of said diaphragm, substantially as and for the purpose described.

23. An acoustic diaphragm, consisting of a sheet of hard elastic metal, provided with an attached impact or wear piece for receiving and transmitting mechanically applied power to forcibly flex the diaphragm, such wear piece comprising clamping members on opposite sides of the diaphragm, secured in

- position by a tension member extending through a perforation in the diaphragm, the surface of engagement between the diaphragm and clamping members being formed and arranged so as to tightly clamp the diaphragm at the center and to leave an annular space for play of the diaphragm between the clamping surfaces at the free edges of the latter, the space for such play being predetermined by and approximately proportional to the maximum proposed amplitude of vibration of the diaphragm when in use, substantially as and for the purpose described.
24. In an acoustic diaphragm formed of metal having a fibrous or grained structure, provided with an anvil secured thereto by riveting and having its impact or wear surface presented for engagement or impact in the direction of trend of the grain of the diaphragm, said anvil having a diaphragm engaging face formed and arranged to clamp the diaphragm adjacent the point of attachment, but beveled or rounded off toward the edge which lies in the direction of the trend of the grain of the diaphragm, substantially as and for the purpose described.
25. An acoustic diaphragm and an attached impact or wear piece for receiving and transmitting mechanically applied power to forcibly flex the diaphragm, such wear piece comprising diaphragm engaging members on opposite sides of the diaphragm, secured in position by a tension member extending through a perforation in the diaphragm, the diaphragm engaging faces of said members being formed or arranged so as to leave a space for play of the diaphragm between the diaphragm engaging surfaces at the free edge of the diaphragm engaging members, the space for such play being predetermined by and approximately proportional to the maximum proposed amplitude of vibration of the diaphragm when in use, substantially as and for the purpose described.
26. An acoustic diaphragm and an attached impact or wear piece for receiving and transmitting mechanically applied power to forcibly flex the diaphragm, such wear piece comprising diaphragm engaging mem-

bers on opposite sides of the diaphragm, secured in position by a tension member extending through a perforation in the diaphragm, the diaphragm engaging faces of said members being rounded at the edge and formed or arranged so as to leave a space for play of the diaphragm between the diaphragm engaging surfaces at the free edges of the diaphragm engaging members, the space for such play being predetermined by and approximately proportional to the maximum proposed amplitude of vibration of the diaphragm when in use, substantially as and for the purpose described.

27. An acoustic diaphragm, formed of relatively thick rolled sheet vanadium steel, provided with an attached impact or wear piece for receiving and transmitting mechanically applied power to forcibly flex the diaphragm, such wear piece comprising a diaphragm engaging member having a diaphragm engaging face made of malleable metal, substantially as and for the purpose described.

28. An acoustic diaphragm, formed of relatively thick rolled sheet vanadium steel, provided with an attached impact or wear piece for receiving and transmitting mechanically applied power to forcibly flex the diaphragm, such wear piece comprising a diaphragm engaging member having a diaphragm engaging face made of malleable metal and rounded at the edges, substantially as and for the purpose described.

29. An acoustic diaphragm, formed of relatively thick rolled sheet vanadium steel, and means for applying power to said diaphragm to forcibly flex the same, said means comprising a diaphragm engaging member made of malleable iron, substantially as and for the purpose described.

Signed at New York city in the county of New York and State of New York this 16th day of November A. D. 1907.
